UNITED STATES PATENT OFFICE.

WELLINGTON PARKER KIDDER, OF BOSTON, MASSACHUSETTS, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,164,942.

Specification of Letters Patent. Patented Dec. 21, 1915.

Application filed April 22, 1909. Serial No. 491,581.

To all whom it may concern:

Be it known that I, WELLINGTON P. KIDDER, a citizen of the United States, residing at Boston, in the county of Suffolk and 5 State of Massachusetts, have invented certain new and useful Improvements in Type-Writing Machines, of which the following is a full, clear, and exact description, such as will enable others skilled in the art to which 10 it appertains to make and use the same.

My present invention relates to typewriting machines and has for its object to provide a new and improved means for effecting relative adjustment between the platen and the printing point, so as to accommodate different thicknesses of work and yet make a clear impression.

It is particularly adapted to the so-called noiseless machine, but is not necessarily restricted to that construction.

Such devices have heretofore been devised by others, but they differ from mine in that the present invention is substantially automatic in its operation. By preference, automatic means adjusting the position of the platen to the thickness of the work is brought into action by the operation of one of the type bars, and I provide automatic locking means for locking the platen in its 30 adjusted position until it is manually released by the operator.

In the accompanying drawings, wherein is illustrated two of various possible embodiments of my invention, Figure 1 represents a side view of a typewriting machine, the frame being shown in section; Fig. 2 is a view of a portion of the front wall of the machine, showing the dial; Fig. 3 is a view similar to Fig. 1 with the parts 40 in another position; Fig. 4 shows the dial illustrated in Fig. 2 with the coöperating pointer in another position; Fig. 5 is a front view of a modified form of the adjusting mechanism for the platen, the view being taken substantially on line 5—5 of Fig. 6, looking in the direction of the arrow; Fig. 6 is a side view of the devices shown in Fig. 5, showing the locking device 45 for the movable tie-rod unlocked; Fig. 7 is illustrative of the devices shown in Fig. 6, with the parts in another position; and Fig. 8 shows the parts of Fig. 7 after the locking device has been operated.

Referring now to the drawings, 1 repre-

sents the frame of the machine having a 55 bed or plate 2 and a front rigid wall 3, the latter being provided with a ledge 4 for supporting a plurality of blocks 5 to which are pivoted the actuating mechanisms for the type-bars. The actuating mechanism 60 comprises a toggle-cam 6 having connected thereto a link 7, the latter being in turn connected at the other end to the type-bar 8 which travels in suitable guides on the top plate 2. Each type-bar is provided with a 65 plurality of types; in the present instance, three, the central one of which is shown at 10. Each of the various toggle-cams is operated, by suitable connections, with the key-levers 11, pivoted on the bar 12. The 70 key-levers rest upon the universal bar 13 and are held in raised positions by the universal bar arms 14, which are mounted on the universal shaft 15.

Extending longitudinally of the machine, 75 in the central portion thereof, is an endwise movable member or center-tie 16 the rear end of which extends upward, as at 17, to form a backing for the platen carriage 18, the latter being horizontally and vertically 80 movable with respect to the abutment 17 through the interposition of a suitable block 20 which slides in vertical guides formed in the abutment, and said block receives a horizontally extending member 21 forming 85 a part of the platen carriage. The platen carriage rides upon the rail 22 which is provided with downwardly extending arms 23 connected with the shift mechanism (not herein shown). By means of this construction it will be noted that the platen carriage is free to move horizontally for letter spacing, or vertically when the upper or lower case types are employed. The forward end of the center-tie extends through suitable 90 ways or guides 24, and the rear end thereof is provided with a roller 25 which rolls upon the horizontal surface 26 of the frame of the machine. The carriage supports a platen roll 27 and the printing platen 28 100 which, as shown, lies in contact with the platen roll and conforms to the contour thereof.

To the center-tie 16 is attached one end of a coil spring 30, the other end of which is attached to the frame of the machine at 31. This spring, which is one of considerable strength, draws the center-tie and the car-

riage constantly toward the front, the forward end of the center-tie resting against the end 32 of a rod 33 whose forward end 34 is threaded in the front wall of the machine. This rod opposes the forward movement of the center-tie against the tension of the spring 30. The forward end of rod 33 is provided with a pointer 35 which coöperates with a dial 36 on the frame of the machine. The rod 33 is encircled by a coil spring 37 one end of which is attached to the rod at 38 and the other end to the frame at 40. This spring constantly urges rod 33 to rotate in such direction that when the center-tie is moved rearwardly, as will hereinafter be explained, the thread upon the rod causes it constantly to follow the center-tie, remain in engagement therewith and prevent a forward movement thereof under the influence of spring 30.

Having described the construction of this embodiment of my invention, the operation thereof is substantially as follows: Figs. 1 and 2 of the drawings represent the parts in the normal position, that is, with the platen substantially in the common plane assumed by the faces of the types when they are moved to impression. With the platen in this position, the face of the types will preferably just clear the printing platen 28 or barely engage therewith when the type-bar has been thrust forward into printing position, and at this point it may be observed that the type-bars have limited throws in the direction of the platen and are arrested when the toggle cam 6 is moved to the position shown in Fig. 3 of the drawings. In the position shown in Figs. 1 and 2, the center-tie 16 assumes its extreme position toward the left, being urged to such position by means of the coil spring 30 and held against further movement by its engagement with the end 32 of rod 33, the pointer 35 being in the position shown in Fig. 2, resting against a stop-pin 41 provided upon the dial.

In order to set the platen to the desired position for any number of impression sheets, as shown, for example, in Fig. 3, the sheets are inserted in the platen carriage in front of the printing platen 28. A type-bar is then thrust from the position shown in Fig. 1 to the position shown in Fig. 3, and when near the end of the stroke, the face of the type will be pressed against the outside impression sheet and the type-bar, continuing its movement, will push the printing platen, carriage and center-tie back against the tension of spring 30 until it assumes the position shown in Fig. 3, which will be the position required for effecting the proper degree of pressure upon that particular thickness of work. During the rearward movement of the center-tie 16, the end 32 of rod 33 will follow the center-

tie, owing to the rotative movement thereof compelled by the spring 37, and said rod will prevent a forward movement of the center-tie when the platen is located in the desired printing position. Then, when the type-bar is retracted, the carriage and center-tie will remain in the position shown in Fig. 3 until the rod 33 is rotated in a reverse direction by the operator and the pointer assumes a zero position with respect to the dial; whereupon spring 30 will return the tie-rod and platen carriage to normal position.

In the embodiment of my invention disclosed in Figs. 5 to 8 inclusive, the center-tie is shown at 16 and is supported in the top plate 2 and urged toward the front of the machine by means of the retractile spring 30 attached to the bracket 42 depending from the top plate. In bracket 42 is threaded a stud screw 43 which may be held in any adjusted position by means of a check or lock nut 44. Stud screw 43 is provided with a projecting end 45 which fits in an opening 46 provided in the forward end of the center-tie. The end of the stud screw abuts the forward end of the center-tie. The stud screw 43 fits the opening 46 in the center-tie with a sliding fit, so that the center-tie is free to move forward or rearward with respect thereto. Stud screw 43 is initially adjusted so as to allow spring 30 to bring the center-tie and the printing platen 28 to the zero position, in which position the face of a type-bar, when projected to impression, will just strike or barely clear the platen.

In the operation of this embodiment of the invention the paper is inserted, as before, in front of the platen, and the type-bar 8 is then thrust forward from the position shown in Fig. 6 to that shown in Fig. 7. Just before reaching the printing point and completing its throw, the face of the type-bar will strike the paper and push the printing platen toward the rear, moving the platen to the correct printing position so that the paper will receive the proper degree of pressure to effect printing; the center-tie is then locked, whereby the platen is maintained in such position, as will now be described.

When a key-lever has depressed the universal bar 13 to the position shown in Fig. 7, the cam roller 47 on the arm 48 will have rocked the cam 6 downward and in that position the type face will be in printing position. By moving the roller 47 and arm 48 from the position shown in Fig. 7 to that shown in Fig. 8, no further movement will be given to the cam 6, since the roller moves in the "dwell" or inactive part of the cam. In the position shown in Fig. 7, the universal bar will just touch the end 50 of a lever 51 which is pivoted on a stud 52. The outer end of the lever 51 abuts against the bracket

53 fixed to the frame of the machine. Lever 52 is provided with an upwardly extending member 54 to which is connected a rod 55, and rod 55, at its opposite end, is connected to a vertically sliding rod 56 which passes through an opening in the center-tie 16. Rod 56 is provided with an enlarged head 57 above the top surface of the center-tie, and passes through the center-tie adjacent the stud screw 43. The center-tie 16 is split as shown at 58, Fig. 5. An extensible coil spring 60 surrounds rod 56 and presses the head 61, attached to the lower end of the rod, downward, the spring re-acting against the bracket 42. The operation of this last-described mechanism is as follows: The platen 28 and center-tie 16, having been pressed back by the type face and the key-lever 11, having been brought to position shown in Fig. 7, where the cam roller 47 has just entered the "dwell" in the cam groove 6, by the continued downward motion of the key-lever 11 from the position in Fig. 7 to that of Fig. 8, the universal bar 13 will strike the end 50 of lever 52 and move that lever together with arm 54, to the position shown in Fig. 8. The toggle formed by arm 54 and rod 55 will then spring to the left through the influence of spring 60, and the rod 56 with its head 57 will move downward a little from the position shown in Fig. 7 to that in Fig. 8, the head 57 clamping the upper split portion of the tie upon the stud screw 43. This exerts a sufficient amount of friction upon the stud screw to hold the center-tie from being drawn to the left to its zero position by the spring 30. Spring 30, however, is of sufficient tension to hold the center-tie and the platen in a position of rest during the printing operation, the friction exerted by the clamped head adding to its stability.

When it is desired to shift the printing platen 28 to another position, as when thinner paper is used, it is necessary to unclamp the locking device, which may be done by lifting the handle 62 toward the rear of the machine, thus moving the locking device from the position of Fig. 8 to that of Fig. 7. When these parts have been restored to the position of Fig. 7, spring 30 will move the center-tie to the left until the abutting surface of the center-tie strikes the end of stud screw 43, thus bringing the center-tie and printing platen to zero position.

It will, accordingly, be seen that I have provided mechanism well adapted to attain the several ends and objects of the invention which will operate with a high degree of efficiency.

An important advantage secured by the embodiments of the invention just described resides in the fact that the adjustability of the platen and its locking in place with respect to the type faces are substantially au-

tomatic, requiring little care or attention on the part of the operator.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, the combination of type bars, and a platen with means whereby the platen may be adjusted to proper printing position by the type bars. 80
2. In a typewriting machine, the combination of type bars, a platen with means whereby the platen may be adjusted to proper printing position by the type bars, and means for holding the platen in adjusted position. 85
3. In a typewriting machine, the combination with the type bars, of a platen, means whereby said platen may be adjusted to proper printing position by the type bars, and means for automatically holding the platen in adjusted position. 90
4. In a typewriting machine, the combination with the type bars movable to a common printing plane, of a platen movable to and from the normal printing plane, said platen being adapted to be moved rearwardly by the type bars, and means for holding the platen against forward movement when the same has been moved rearwardly. 100
5. In a typewriting machine, the combination with the type bars movable to a common printing plane, of a platen movable toward and from the normal printing plane, said platen being adapted to be moved rearward with respect to the printing plane by a type bar, means for holding the platen against movement when the same has been moved rearward, and means for restoring the platen to normal position. 105
6. In a typewriting machine, the combination with the type bars movable to a common printing plane, of a platen movable rearwardly with respect to the normal printing plane, said platen being adapted to be so moved by the type bars, means for holding the platen in a rearward position, and means for restoring the same to normal position. 115
7. In a typewriting machine, the combination with a platen movable toward and from a normal printing plane, of type bars which have a limited throw toward the platen, said type bars being adapted to move the platen rearwardly to a position dependent upon the number of impression sheets interposed between the platen and the faces 125 130

of the type bars, and means for holding the platen fixed against forward movement when the same has been moved rearwardly.

8. In a typewriting machine, the combination with type bars having limited throws in the direction of the platen, of a platen adjustable rearwardly with respect to the plane occupied by the faces of the types when they are moved to impression to such position as will enable the type bars to apply the proper amount of printing pressure upon a plurality of impression sheets interposed between the platen and the type faces, means for holding the platen against further recession when the printing pressure is applied thereto by the type bars, and means for holding the platen against forward movement when the same has been moved rearwardly.

20 9. In a typewriting machine, the combination with a platen, of a plurality of type bars each of which has a limited throw in the direction of the platen, an abutment for the platen, said abutment being movable, whereby the platen may be caused to recede from the normal printing plane to such position as will permit of the required printing pressure to be applied to the impression sheets interposed between the platen and the faces of the types, said platen being adapted to be moved to such position by pressure applied to the outermost of the impression sheets by any of the type bars, and means for holding said abutment in the position to which it is moved to carry the platen to the above-mentioned position.

10. In a typewriting machine, the combination with the type bars each of which has a limited printing movement in the direction of a platen, an abutment for the platen, said abutment being movable to allow the platen to recede from a normal printing plane when one or more sheets are interposed between the platen and the type bars and the outermost impression sheet is engaged by a face of the type bar, means for effectively resisting further recession of the abutment during printing, whereby the platen is held against recession, and means coöperating with said abutment to hold the platen in the above-mentioned position.

11. In a typewriting machine, the combination with type bars adapted to print by pressure, of a platen movable at right angles to the printing plane, an abutment located behind the platen adapted to be moved rearwardly to permit a corresponding rearward movement of the platen under the action of the type bars when a plurality of impression sheets are positioned thereon and said impression sheets are engaged by one of the type bars, whereby the platen may be moved to such position as will permit proper printing pressure to be applied by the type bars to any number of sheets positioned upon said

platen, means for effectively preventing a recession of the platen during the application of printing pressure thereon, and means for preventing a movement of said platen toward the printing plane.

12. In a typewriting machine, the combination with type bars having a limited throw in the direction of the platen, whereby their faces occupy a common plane when the type bars are moved to impression, of a platen adapted normally to lie in juxtaposition to said plane, whereby the proper printing pressure may be applied to an impression sheet or sheets of given thickness interposed between the platen and the faces of the types, said platen being movable rearwardly by the engagement of a type bar with an impression sheet or sheets of greater thickness to such position as will enable the type bars to apply the proper printing pressure thereto.

13. In a typewriting machine, the combination with type bars having a limited throw in the direction of the platen, whereby their faces occupy a common plane when the type bars are moved to impression, of a platen adapted normally to lie in juxtaposition to said plane, whereby the proper printing pressure may be applied to an impression sheet or sheets of given thickness interposed between the platen and the faces of the types, said platen being movable rearwardly by the engagement of a type bar with an impression sheet or sheets of greater thickness to such position as will enable the type bars to apply the proper printing pressure thereto, means for effectively preventing the further recession of the platen under the printing pressure, and means for holding the platen in the position to which it has been moved by a type bar.

14. In a typewriting machine, the combination with the type bars and the platen, of a device extending rearwardly through the machine intermediate the sides thereof and having a portion thereof extending upwardly behind the platen to form an abutment therefor, said device being movable rearwardly, whereby the platen may be correspondingly moved with respect to a normal printing plane, means coöperating with said device to hold the platen against recession when the same is engaged by the type bars, and means for coöperating therewith for preventing a movement of the platen toward the normal printing plane when the same has been moved rearwardly.

15. In a typewriting machine, the combination with type bars, of a platen, said type bars and said platen being mounted for relative adjustment with respect to the printing plane, and said adjustment being effected by the engagement of a type bar with an impression sheet or sheets interposed between the platen and the faces of the types.

16. In a typewriting machine, the combination with a platen and type bars with supports therefor, said type bars having throws of pre-determined lengths in the direction of the platen, said platen and the support for the type bars being capable of relative movements with respect to the common plane occupied by the faces of the types when the type bars are thrust to the impression point, such relative movement being effected by the engagement of the face of a type of any of the type bars with an impression sheet or sheets positioned upon the platen, whereby the proper printing pressure may be applied to said impression sheet or sheets by the type bars, and means interposed between the support for the type bars and the platen adapted to maintain said parts in position after the aforesaid relative movement has been effected.

17. In a typewriting machine, the combination with a platen adapted to carry impression sheets, and type bars adapted to co-act with the impression sheets, of an abutment located behind the platen adapted effectively to prevent yielding of the platen when the sheets are engaged by the type bars, said abutment being movable rearwardly to permit of a corresponding movement of the platen, spring means engaging said abutment to urge the same to movement in a forward direction, and means for positively preventing such forward movement.

18. In a typewriting machine, the combination with a platen and type bars, each of the latter members having a throw of pre-determined length in the direction of the platen, a member extending rearwardly through the machine and then upward behind the platen to form an abutment therefor, spring means for urging said member to such movement as would cause the platen to move forwardly with respect to the printing plane, and means engaging said member adapted to prevent such forward movement of the platen.

19. In a typewriting machine, the combination with a platen and direct-thrust type bars, each of the latter members having a throw of predetermined length in the direction of the platen, a member extending rearwardly through the machine and then upward behind the platen to form an abutment therefor, spring means for urging said member to such movement as would cause the platen to move forwardly with respect to the printing plane, and adjustable means engaging said member adapted to prevent such forward movement of the platen.

20. In a typewriting machine, the combination with a platen and type bars, each of the latter members having a throw of pre-determined length in the direction of the platen, a member extending rearwardly through the machine and then upward be-

hind the platen to form an abutment therefor, spring means for urging said member to such movement as would cause the platen to move forwardly with respect to the printing plane, and automatically adjustable means engaging said member adapted to prevent such forward movement of the platen.

21. In a typewriting machine, the combination with a platen adapted to carry a plurality of impression sheets, type bars adapted to co-act therewith, means anchored in the frame of the machine for resiliently tying said platen against the normal action of said type bars, means whereby said resilient tying means may be lengthened, and means for preventing the shortening thereof.

22. In a typewriting machine, the combination with a platen adapted to carry impression sheets, a type bar having a limited throw toward said platen and adapted to co-act with said sheets, means whereby said platen may be moved relatively to a normal printing plane as said type bar co-acts with the impression sheets, and means for preventing a return movement of said platen after printing has been effected.

23. In a typewriting machine, in combination, a platen, a tie-rod for the platen, means whereby the effective length of said tie-rod may be increased, and means for automatically preventing a shortening thereof.

24. In a typewriting machine, the combination with the platen and a plurality of type bars, of actuating mechanism for the type bars, a support therefor, tension means extended between the support of the actuating mechanism and the platen, means whereby the effective length of said tension means may be increased, and means for preventing a shortening of said tension means.

25. In a typewriting machine, the combination with a platen and a plurality of type bars adapted to print by pressure, of an abutment disposed behind the platen, tension means extended between said abutment and a fixed portion of the framing of the machine, means whereby the effective length of said tension means may be increased under the action of said type bars, and means for preventing a contraction of the tension means when the same has been extended.

26. In a typewriting machine, the combination with a platen and a plurality of type bars adapted to effect printing by pressure, of a movable abutment disposed behind the platen, tension means connecting said abutment with a fixed portion of the framing of the machine, means whereby said tension means may be expanded to allow said abutment to be moved rearwardly under the action of said type bars, and means for automatically preventing a contraction of said tension means.

27. In a typewriting machine, the combi-

nation with a platen adapted to carry impression sheets and a plurality of type bars adapted to print by pressure, of an abutment located behind the printing point of the platen, movable bodily toward or from the common plane assumed by the faces of the type when projected to impression, said abutment being adapted to be moved from said plane when the impression sheets are engaged with a type bar, and means for holding said abutment against movement in an opposite direction when the same has been moved from said plane.

28. In a typewriting machine, the combination with a platen adapted to carry impression sheets and a plurality of type bars adapted to print by pressure, of an abutment located behind the printing point of the platen, movable bodily toward or from the common plane assumed by the faces of the type when projected to impression, said abutment being adapted to be moved from said plane when the impression sheets are engaged with a type bar, and means for automatically holding said abutment against movement in an opposite direction when the same has been moved from said plane.

29. In a typewriting machine, the combination with type bars, of a movable platen, an abutment erected behind the printing point of the platen, spring means connecting said abutment with a fixed portion of the machine and urging the same to forward movement, and means engaging said abutment which prevents such forward movement.

30. In a typewriting machine, the combination with direct thrust type bars, of a platen, a movable tie rod extending longitudinally of the machine and then upward to form a backing for the platen, spring means for urging said tie rod to forward movement, and a threaded rod abutting the forward end of the tie rod and normally holding the same in such position that the platen will be located substantially in the plane assumed by the faces of the types when the type bars are thrust to impression, said threaded rod being adapted to follow the tie rod when the same is moved rearwardly and hold it in any position to which it may be moved.

31. In a typewriting machine, the combination with the platen, of a plurality of type bars adapted to print by pressure, of an endwise movable member extending longitudinally through the machine and then upward to form an abutment for the platen, spring means for urging said member to forward movement, a member threaded in a fixed portion of the framing of the machine and abutting said movable member, and means for causing said threaded member to follow said endwise movable member when the same is moved rearwardly to hold

the latter in any position to which the same is moved.

32. In a typewriting machine, the combination with a platen carriage carrying the platen, and a plurality of endwise movable type bars adapted to print by pressure, of an endwise movable member suitably supported and guided in the machine which extends longitudinally therethrough and then upward behind the platen carriage to form an abutment therefor, a spring attached to said member adapted to urge the same to forward movement, and a rod having one end threaded in the fixed portion of the machine and the other end abutting said endwise movable member, and means for causing a rotative movement of said rod when said endwise movable member is moved rearwardly, whereby the threaded rod will follow the endwise movable member and automatically maintain the same against forward movement when the same is moved rearwardly.

33. In a typewriting machine, the combination with the platen, and endwise movable type bars, of an endwise movable member which extends rearwardly through the machine to form an abutment for the platen, spring means for urging said member to forward movement, a rod having one end threaded in a fixed portion of the machine and the other end abutting the forward end of said member, means for urging said rod to rotation when said member is moved rearwardly, whereby said rod will remain in constant engagement with the member and hold the same automatically in any position to which the same may be moved, a scale adjacent the forward end of said rod, a pointer upon said rod which cooperates with said scale, and means for arresting the rotative movement of said rod when the same is moved to zero position.

34. In a typewriting machine, the combination with a plurality of type bars, of a platen, movable toward and from the faces of the type, a member extending longitudinally in the central portion thereof and then upwardly to form a backing for the platen, a spring attached to said member and to a fixed portion of the machine and urging the member to forward movement, a rotatable rod having one end threaded in a fixed portion of the frame of the machine and the other end in engagement with the forward end of said member, a scale arranged adjacent said rod, an indicator carried by said rod which cooperates with said scale to indicate to the operator the position of the platen with respect to the printing plane, and means for arresting the rotative movement of said rod in a position such that the platen will be in a normal printing plane.

35. In a typewriting machine, the combi-

- nation with type bars and a platen, of automatic means, brought into action by operating a type bar, for adjusting the distance between the platen and the printing point for the type; whereby the space between the platen and the type faces may be automatically adjusted for different thicknesses of work.
36. In a typewriting machine, the combination, with a platen adjustable toward and away from the printing point and a series of type bars, of means, automatically brought into action by operating a type bar, for adjusting the position of the platen relative to the printing point, automatic means for locking the platen in its adjusted position and manually operated means for releasing it therefrom; whereby the actuation of a type bar adjusts the distance

between the platen and the printing point 20 to the thickness of the work and such distance is maintained until changed by the operator.

37. In a typewriting machine, the combination, with a platen and a series of type 25 bars, of automatic means for adjusting the distance between the platen and the printing point for the type in accordance with the thickness of the work, automatic locking means for maintaining the adjusted distance, and a manually operated device for releasing the lock at desired times.

In testimony whereof I affix my signature, in the presence of two witnesses.

WELLINGTON PARKER KIDDER.
